UNITED STATES PATENT OFFICE

TOMLINSON F. JOHNSON, JR., OF ATLANTA, GEORGIA

DISCONNECTING AIR-BREAK SWITCH

Application filed March 18, 1924, Serial No. 700,112. Renewed May 21, 1929.

This invention relates to disconnecting switches of the air break type, particularly designed for use upon high tension transmission lines.

Most of the switches now used for this purpose are operated by a system of links and levers, which require so much power for their operation that the blade must be made as light as possible, or it is very difficult to open or close it. Attempted improvements along these lines have resulted in expensive and complicated constructions, which are entirely impractical. Either the lightness of the blade and the light pressure of the same against the contacts causes the blade to be burned off, or the strain resulting from its operation causes the insulator to break.

The principal objects of the present invention are to provide a switch of heavy and rugged construction which makes a firm contact, and has, therefore, a large current carrying capacity, which may be opened and closed quickly, thus keeping the resulting arc at a minimum, and which may be operated without causing excessive strain on the insulators.

The switch which constitutes the present invention is especially adapted to be used in connection with the contacting jaws disclosed in my co-pending application, Serial No. 675,367, filed November 17, 1923, now Patent 1,560,165, dated November 3, 1925, but is not necessarily limited thereto.

The invention consists further in various details of construction and combinations of elements which will be more particularly described in the following detailed description taken in connection with the accompanying drawings, which illustrate the invention in its preferred form.

40 In the drawings:

Figure 1 is a perspective view illustrating the switch in closed position.

Figure 2 is a similar view with the switch in open position.

Figure 3 is a plan view of the switch in closed position.

Figure 4 is a similar view with parts shown in section.

50 Figure 5 is a side elevation of the switch

supporting and operating means with the switch in closed position.

Figure 6 is a similar view with the switch being opened.

Figure 7 is a detail sectional view illustrating the means for completing the opening movement, and for cushioning the same.

Fig. 8 is a plan view of the switch actuating means, with the switch in open position.

Figure 9 is a perspective view of the switch, showing its special adaptation for gang operation.

In the embodiment of my invention shown in the drawings, the switch and its operating means are supported upon a suitable bar 10, which is in alignment with the conductor and supported at the top of a tower or pole of the transmission line. Insulators 11 and 12 are secured to opposite ends of the bar 10, and have supporting brackets 13 and 14 secured thereto, which are preferably of bronze. One of the brackets, as 13, has a lug 15 to which the end of the conductor 16 is secured, and carries contacting jaws 17, preferably of the type disclosed in my co-pending application above referred to, and electrically connected to the bracket 13 by conductor loops 18.

The other supporting bracket 14 has a lug 19 to which the end of the other conductor 20 is secured, and carries upstanding spaced ears 21 to which one end of a supporting bar 22 is secured by a pin 23, or other suitable means, this bar being electrically connected to the bracket by a suitable conductor loop 24. The other end of the bar 22 is formed into a yoke 25, between the arms of which the switch blade 26 is pivotally supported by a pin 27 or the like, the blade being electrically connected to the bar 22 by a suitable conductor loop 28.

The extremity of the bar 22 is curved 90 downwardly and formed into an eye 29, which receives a headed pin 30 secured to a boss 31, which projects upwardly from a bracket 32 secured to the middle insulator 33.

The insulator 33 is mounted for rocking 95 movement about a vertical axis, and the bracket 32 carries a cam 34, which may be formed integral therewith and rotates with the insulator to open or close the switch blade 26. The cam 34 has on its upper face an in-

clined surface 35, which, when the cam is rocked toward the left from the position shown in Figure 1, engages the lower edge of the switch blade 26, and forces the same out of the jaws 17. The bracket 13 is provided with the usual horn 36 to lessen the formation of arcs between the switch blade and the contact jaws.

The switch blade 26 is extended rearwardly 10 beyond the pivot pin 27 to form a heel 37, adapted to be engaged by the peripheral surface 38 of the cam 34 to effect the initial closing movement of the switch blade. The cam is eccentrically mounted, as best shown in 15 Figure 8, and as it is rotated in a contra-clockwise direction, the heel 37 is forced outwardly and upwardly, and the blade 26 is carried downwardly toward the contact jaws 17 until the heel engages the upwardly inclined 20 surface 39 of the cam, which is on the opposite side of the inclined surface 35, and completely closes the switch. The closing movement of the cam is limited by a lug 40 having an up-standing shoulder, which engages the side of 25 the heel 37 when the blade reaches its fully closed position.

In order to hasten and facilitate the opening movement of the switch blade, the latter is provided on its back, near the pivot pin 27, 30 with an ear 41, which is pivotally connected to a socket 42 secured to the end of a plunger rod 43, which projects into a barrel 44 and terminates in a plunger head 45. An expansive coiled spring 46 surrounds the rod 43 35 within the barrel and acts between the plunger head 45 and the head 47, through which the rod 43 passes, to jerk the switch blade upwardly as soon as it is released from the jaws 17. The rear end of the barrel 44 is 40 closed by a cap 48 to form an air cushion in the end of the barrel, between said cap and the plunger head 45 to check the movement of the blade, and to cushion the same and prevent injury to the insulators. The barrel 44 45 is securely and adjustably held in a clamp arm 49, which is pivotally connected at 50 to the bar 22, so as to permit the barrel to have a rocking movement to follow the arcuate path of the end of the rod 43, which is 55 connected to the switch blade.

The middle insulator 33, which supports the cam 34, is supported for rocking movement by means of a pin 51, which extends vertically downwardly through the bar 10, 55 and is there provided with a sleeve 52 to which is connected a socket 53 for receiving the end of a suitable tool 54 by means of which the insulator may be rocked, and the switch opened or closed by a person standing on the ground.

60 The circuit usually consists of three or more conductors, each of which is provided with a switch, and it is desirable to have these switches connected in gangs, so that they may all be operated simultaneously. The switch 65 herein described is well adapted for such op-

eration, and for this purpose, as best shown in Figure 9, a collar 55, secured to the pin 51, is provided with means for attaching a lever arm 56, which is provided with perforated ears 57 adapted to be connected by links 58 70 to similar crank arms on the middle insulators supporting the other switches.

It is to be particularly noted that in the present invention the link and lever mechanism, which has been found so inefficient in previous constructions, is entirely eliminated, and the switch is opened and closed by a cam or wedge action by means of which great power may be obtained with a minimum effort on the part of the operator, and with little strain on the insulator. This superior feature is obtained without sacrificing or diminishing in other respects the quality and efficiency of the switch. In fact, my switch opens more quickly than other switches, since 80 as soon as the cam action releases the blade from contact with the jaws, the spring jerks it open. The speed at which this takes place keeps the resulting arc at a minimum, and the switch can consequently be used on circuits carrying more load than switches of different construction. Owing to the cam or switch action, the operator does not have to raise the weight of the blade, consequently the blade can be made heavy and rugged, 95 and of large current carrying capacity. The switch also closes with a very high speed, using the momentum of the blade to force it into contact with the jaws. The latter can, therefore, be adjusted so that the contact 100 will be very tight. The switch may be closed by slamming, and there will be no recoil against the insulator. Since the blade in opening moves through a comparatively short arc when it is released from the jaws and opened by the action of the spring, it is only necessary to move the cam through an arc of approximately 90° between opening and closing positions.

While I have shown and described the 110 structural details of the preferred embodiment of my invention it is to be understood that this is merely illustrative, and that various modifications may be made therein without departing from the salient features of 115 the invention, or sacrificing any of its advantages. I do not, therefore, desire to be limited to this precise construction, but intend to cover by the appended claims all such modifications as are within the spirit and 120 scope of my invention.

What is claimed is:

1. In a disconnecting switch, the combination with a pivoted switch blade and jaws with which the same is adapted to contact, of a cam mounted for rocking movement about an axis which is transverse to the axis of said blade and having a face engageable with said blade to force it open when the cam is rocked in one direction, and another 125

face engageable with the blade on the opposite side of the pivot to close it when the cam is rocked in the opposite direction.

2. In a disconnecting switch, the combination with a pivoted switch blade and jaws with which the same is adapted to contact, of a cam mounted for rocking movement about an axis which is transverse to the axis of said blade and having a face engageable with said blade to force it out of contact with the jaws when the cam is rocked in one direction, and a spring operable to jerk the switch blade to wide open position as soon as it is released from the jaws, said cam having another face engageable with the blade on the opposite side of the pivot to close it when the cam is rocked in the opposite direction.

3. In a disconnecting switch, the combination with a pivoted switch blade and jaws with which the same is adapted to contact, of a cam mounted for rocking movement about an axis which is transverse to the axis of said blade and having a face engageable with said blade to force it out of contact with the jaws when the cam is rocked in one direction, and a spring operable to jerk the switch blade to wide open position as soon as it is released from the jaws, and means for cushioning the blade as it approaches its wide open position, said cam having another face which is engageable with the open blade to close it when the cam is rocked in the opposite direction.

4. In a disconnecting switch, the combination with a pivoted switch blade and jaws with which the same is adapted to contact, of a cam mounted for rocking movement about an axis which is transverse to the axis of said blade and having a face engageable with the under side of the blade to force it out of said jaws when the cam is rocked in one direction, a spring operable to jerk the switch blade to wide open position as soon as it is released from the jaws, and an air cushion operable to check the impact of the blade as it reaches the limit of its opening movement, said cam having another face engageable with the blade to close it when the cam is rocked in the opposite direction.

5. In a disconnecting switch, the combination of a switch blade, a cooperating member with which the blade is adapted to contact, insulators on which said blade and cooperating member are supported, one of said insulators being rockable about a vertical axis, and a cam secured to the upper end of the rockable insulator and engageable directly with the blade to open the same when the insulator is rocked in one direction and engageable to close said blade when the insulator is rocked in the opposite direction.

6. In a disconnecting switch, the combination with a pivoted switch blade and jaws with which the same is adapted to contact, of

a cam mounted for rocking movement about an axis which is perpendicular to the axis of the switch blade and having a face engageable with said blade to force it from said jaws when the cam is rocked in one direction, a piston pivotally connected with the blade, a spring operable on the head of the piston to jerk the switch blade wide open as soon as it is released from the jaws, said cam having another face engageable with the blade to close it when the cam is rocked in the opposite direction.

7. In a disconnecting switch, the combination with a pivoted switch blade and jaws between which the same is adapted to be held, of a cam mounted for rocking movement about an axis which is perpendicular to the axis of the switch blade and having a face engageable with said blade to force it out of the jaws when the cam is rocked in one direction, a piston pivotally connected with the blade, a spring operable on the head of the piston to jerk the blade wide open as soon as it is released from the jaws of the movement of the cam, and means for cushioning the blade as it approaches its wide open position, said cam having another face engageable with the blade to close it when the cam is rocked in the opposite direction.

8. In a disconnecting switch, the combination with a pivoted switch blade and jaws between which the same is adapted to be held, of a cam mounted for rocking movement about an axis which is perpendicular to the axis of the switch blade and having a face engageable with said blade to force it out of the jaws when the cam is rocked in one direction, a piston pivotally connected with the blade, a spring operable upon the head of the piston to jerk the switch blade wide open as soon as it is released from the jaws by the movement of the cam, and an air cushion operable to check the impact of the blade as it reaches the limit of its opening movement, said cam having another face engageable with the blade to close it when the cam is rocked in the opposite direction.

9. In a disconnecting switch, the combination of two insulators having a pivoted switch blade supported thereon, a third insulator in alignment with the other two and having jaws supported thereon which normally receive said blade between them, the middle insulator being mounted to rock about a vertical axis, and cam means secured in fixed relation to the middle insulator and engageable directly with the switch blade to open or close the same when said middle insulator is rocked.

10. In a disconnecting switch, the combination of two insulators having a pivoted switch blade supported thereon, a third insulator in alignment with the other two and having jaws supported thereon which normally receive said blade between them, one of the two insulators first mentioned being mount-

ed for rocking movement about a vertical axis beneath the switch blade, a cam secured to the rockable insulator and engageable with the switch blade to open it when the insulator is rocked in one direction, and engageable with the switch blade to close it when the insulator is rocked in the other direction.

11. In a disconnecting switch, the combination of a pair of jaws, a switch blade pivoted to swing in a vertical plane into and out of contact with said jaws to close and open the switch, a cam mounted to rock about a vertical axis and having a surface engageable with the under side of said blade between the blade pivot and said jaws to positively force the blade out of contact with the jaws when the cam is rocked in one direction, said blade having a heel projecting rearwardly beyond its pivot, and said cam having another surface engageable with said heel to close the blade when the cam is rocked in the opposite direction.

12. In a disconnecting switch, the combination with a pair of jaws and a switch blade pivoted to swing in a vertical plane into and out of contact with said jaws to close and open the switch, of a cam mounted to rock about a vertical axis and having a surface engageable with the under side of said blade between the blade pivot and said jaws to positively force the blade out of contact with the jaws when the cam is rocked in one direction, a spring operable to jerk the switch blade to wide open position as soon as it is released from the jaws by the action of the cam, said blade having a heel projecting rearwardly beyond its pivot, and said cam having another surface engageable with the heel to close the blade when the cam is rocked in the opposite direction.

13. In a disconnecting switch, the combination with a pair of jaws and a switch blade pivoted to swing in a vertical plane and adapted when in horizontal position to be held between said jaws, of a cam mounted to rock about a vertical axis and having a surface engageable with the under side of said blade between the blade pivot and said jaws to positively force the blade out of contact with the jaws when the cam is rocked in one direction, a spring operable to jerk the switch blade to wide open position as soon as it is released from the jaws by the action of the cam, means for cushioning the blade as it approaches its wide open position, said blade having a heel projecting rearwardly beyond its pivot, and said cam having another surface engageable with said heel to close the blade when the cam is rocked in the opposite direction.

14. In a disconnecting switch, the combination with a pair of jaws and a switch blade pivoted to swing in a vertical plane into and out of contact with said jaws to close and open the switch, of a cam mounted to

rock about a vertical axis and having a surface engageable with the under side of said blade between the blade pivot and said jaws to positively force the blade out of contact with the jaws when the cam is rocked in one direction, a spring operable to jerk the switch blade into wide open position as soon as it is released from the jaws by the action of the cam, an air cushion operable to check the impact of the blade as it reaches the limit of its opening movement, said blade having a heel projecting rearwardly beyond its pivot, and said cam having another surface engageable with said heel to close the blade when the cam is rocked in the opposite direction.

15. In a disconnecting switch, the combination with a pair of jaws and a switch blade pivoted to swing in a vertical plane into and out of contact with said jaws to open and close the switch, of means engageable directly with the lower edge of the blade for positively releasing the blade from the jaws, spring means for jerking the blade to wide open position as soon as it is released, means for cushioning the blade as it approaches its wide open position, and means for closing the switch.

16. In a disconnecting switch, the combination with a pair of jaws, of a switch blade pivoted to swing into and out of contact with said jaws to close and open the switch, insulators on which the blade and jaws are supported, one of said insulators being rockable about an axis which lies in the plane of movement of said blade, and a cam secured to said rockable insulator, said cam, when rocked in one direction, being engageable with the blade on one side of its pivot to open the same, and when rocked in the other direction engageable with the blade on the other side of its pivot to close the same.

17. In a disconnecting switch, the combination with a pair of jaws and a switch blade pivoted to swing in a vertical plane into and out of contact with said jaws to close and open the switch, of a cam mounted to rock about a vertical axis and having a surface engageable with the under side of said blade between the blade pivot and said jaws to force the blade out of contact with the jaws when the cam is rocked in one direction, a piston pivotally connected with the blade, a spring operable on the head of the piston to jerk the switch blade to wide open position as soon as it is released from the jaws by the action of the cam, said blade having a heel projecting rearwardly beyond its pivot, and said cam having another surface engageable with said heel to close the blade when the cam is rocked in the opposite direction.

18. In a disconnecting switch, the combination with a pair of jaws and a switch blade pivoted to swing in a vertical plane into and out of contact with said jaws to close and open the switch, of a cam mounted to rock

about a vertical axis and having a surface engageable with the under side of said blade between the blade pivot and said jaws to positively release the blade from the jaws when the cam is rocked in one direction, a piston pivotally connected with the blade, a spring operable on the head of the piston to jerk the switch blade to wide open position as soon as it is released from the jaws by the action of the cam, means for cushioning the blade as it approaches its wide open position, said blade having a heel projecting rearwardly beyond its pivot, and said cam having another surface engageable with said heel to positively close the blade when the cam is rocked in the opposite direction.

19. In a disconnecting switch, the combination with a pair of jaws and a switch blade pivoted to swing in a vertical plane into and out of contact with said jaws to close and open the switch, said blade being in a horizontal position when closed, of a cam mounted to rock about a vertical axis and having a surface engageable with the under side of said blade between the blade pivot and said jaws to positively force the blade out of contact with the jaws when the cam is rocked in one direction, a piston pivotally connected with the blade, a spring operable on the head of the piston to jerk the switch blade to wide open position as soon as it is released from the jaws by the action of the cam, an air cushion operable to check the impact of the blade as it approaches a vertical position, said blade having a heel projecting rearwardly beyond its pivot, and said cam having another surface engageable with the heel to positively swing the blade from vertical to horizontal position to close the switch when the cam is rocked in the opposite direction.

20. In a disconnecting switch, the combination with a pair of jaws and a switch blade pivoted to swing in a vertical plane into and out of contact with said jaws to close and open the switch, of means rockable about a vertical axis beneath the blade pivot and engageable directly with the blade to positively release the blade from the jaws when said means is rocked in one direction, means for jerking the blade to wide open position as soon as it is released, means for cushioning the blade as it approaches its wide open position, said rockable means being operable when rocked in the opposite direction to positively close said blade.

21. In a disconnecting switch, the combination with a pair of jaws and a switch blade pivoted to swing in a vertical plane into and out of contact with said jaws to close and open the switch, of means mounted to rock about a vertical axis beneath the blade pivot and operable when rocked in one direction to positively release the switch blade from contact with the jaws, means for jerking the blade to

wide open position as soon as it is released, an air cushion operable to check the impact of the blade as it reaches the limit of its opening movement, said rockable means being operable when rocked in the opposite direction to positively close the switch blade.

22. In a disconnecting switch, the combination with a pivoted switch blade and jaws with which the same is adapted to contact, of a cam mounted for rocking movement and having a face engageable with said blade to force it out of contact with the jaws when the cam is rocked in one direction, and having another face engageable with the blade to close it when the cam is rocked in the opposite direction, and a rock arm secured in fixed relation to said cam and provided with means for connecting it to move in unison with corresponding rock arms of similar switches for gang operation.

23. In a disconnecting switch, the combination with a pair of jaws and a switch blade pivoted to swing in a vertical plane into and out of contact with said jaws to close and open the switch, of a cam mounted to rock about a vertical axis and having a surface engageable with the under side of said blade between the blade pivot and said jaws to positively force the blade out of contact with the jaws when the cam is rocked in one direction, said blade having a heel projecting rearwardly beyond its pivot, said cam having another surface engageable with the heel to close the blade when the cam is rocked in the opposite direction, and a rock arm secured in fixed relation to said cam and provided with means for connecting it to move in unison with corresponding rock arms of similar switches for gang operation.

24. In a disconnecting air break switch for high tension transmission lines a pivoted switch blade, jaws with which said blade is adapted to contact, spring means pivotally connected to said blade and normally urging it to open, and a compound cam engageable with the switch blade on opposite sides of the pivot; said cam having a face portion adapted to initiate the opening movement of the switch blade to release it from the jaws so that said spring means will snap the blade open, and another face on the cam adapted to engage the switch blade on the opposite side of the pivot to close it.

25. In a disconnecting air break switch for high tension transmission lines a pivoted switch blade; blade gripping jaws with which said blade is adapted to contact; means normally urging the blade to open; a movable insulator mounted adjacent to the pivoted end of the blade; and a cam mounted on said insulator having portions to engage the blade on opposite sides of the pivot, one portion being arranged initially to release the blade from the gripping jaws and the other portion being arranged to close the blade.

26. In a disconnecting air break switch for high tension transmission lines a pivoted switch blade; blade gripping jaws with which said blade is adapted to contact; means normally urging the blade to open; a movable insulator mounted adjacent to the pivoted end of the blade; and a compound cam secured to said insulator having cam surfaces slidably engageable with the switch blade on opposite sides of the pivot, one of the cam faces being 10 constructed and arranged to initiate opening movement of the blade and the other cam face being constructed and arranged to close the blade.

18 In testimony, that I claim the foregoing as my own, I have hereto affixed my signature.
